UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,375,712.

Specification of Letters Patent. Patented Apr. 26, 1921.

Application filed March 25, 1918. Serial No. 224,497.

To all whom it may concern:

Be it known that I, ALBEN E. LUNDELL, a citizen of the United States, residing at New York, in the county of Bronx, State of 5 New York, have invented certain new and useful Improvements in Telephone-Exchange Systems, of which the following is a full, clear, concise, and exact description.

This invention relates to telephone exchange systems in which manual lines provided with the usual manual station equipment, and automatic lines provided with the necessary substation apparatus for controlling automatic switches are arranged to terminate in a common exchange, and to be served in part by the same switching and controlling apparatus employed therein in the extension of telephone connections.

The manual subscribers' lines belonging 20 to an exchange of this character are arranged to terminate before operators' positions, and the operator may be provided with suitable connecting means, such as cord circuits, whereby she is enabled to extend 25 connections from calling lines to other lines of the same exchange whether of the manual or automatic type. The automatic subscribers' lines terminate in line or finder switches at the exchange, and are provided 30 with the usual substation calling dial by means of which the calling subscriber controls the operation of the selective switches to complete a connection to other lines of his own exchange.

More particularly, the arrangement of 35 circuits and controlling apparatus involving the novel features of the present invention are embodied in a telephone system including a plurality of private branch exchanges, 40 each of which is adapted to serve both manual and automatic subscribers' lines in accordance with the foregoing general description.

The object of the invention consists in the 45 provision of trunking or connecting circuits in such a system whereby a call originating on a subscriber's line individual to one private branch exchange may be extended to a second private branch exchange, and 50 through the agency of switching devices thereat, extended to the desired line individual to the second exchange. The inter-exchange trunks are preferably one-way connecting circuits and are available in either 55 manual or dial subscribers' stations. The

outgoing end of these trunks terminates at the originating exchange in spring jacks at an operator's position, so that in case a manual subscriber desires connection with a subscriber in a distant private branch exchange, 60 she may connect his line, by means of her cord circuit, to the interexchange trunk. The operator is equipped with calling mechanism in order to control the switches in the distant exchange over the trunk circuit. The 65 outgoing end of the trunks also terminates at the originating exchange in the multiple terminals of selector switches so that in case the subscriber of an automatic line wishes to converse with a subscriber individual to 70 the second private branch exchange he is enabled to manipulate his calling dial, as when making calls local to his own exchange, to extend his line to the distant exchange. By a further operation of his sending device he may then direct the switches in said exchange to connect his line with any subscriber's line terminating therein in a manner similar to that above described in connection with calls completed by an operator. 80

A feature of the invention is the provision of a trunk circuit between private branch exchanges, in accordance with the above mentioned object, which normally remains 85 in a non-talking condition during the calling period, and is arranged to transmit current impulses over its two conductors in series from the originating to the distant exchange, either under the control of a subscriber's transmitter in the case of an automatic call, or the operator's sending apparatus when a manual line is being extended. After the connection has been completed and the called party responds, certain changes 90 are effected whereby the trunk is automatically converted from a condition adapted to the transmission of calling currents into 95 one suitable for the transmission of voice currents. 100

Another feature resides in the provision of means whereby the operator in the originating exchange is given supervision of a called line in a distant exchange through the agency of current changes produced in the 105 trunk circuit employed in establishing the connection between the exchanges.

Other objects of the invention will become apparent from a consideration of the following description and the appended claims. 110

In the drawings, Figure 1 shows a private branch exchange in which manual station lines are associated with operator's switching apparatus, and in which calling dial station lines are terminated in automatic switches. This figure illustrates in particular only that portion of the exchange equipment involved in extending calling lines to outgoing connecting circuits leading to distant exchanges of the same general character, and accordingly the outgoing end of an interexchange trunk is shown terminating at an operator's position, and in the multiple of automatic switches; Fig. 2 shows a distant private branch exchange in which the incoming end of the trunk terminates in a selector switch, together with the circuits and operating mechanism arranged to be controlled over the trunk circuit by current impulses produced at the originating exchange; and Fig. 3 shows the circuits and operating parts of a final selector switch in the second exchange adapted to complete the connection to a called line.

It is believed a more thorough comprehension may be had of the advantageous trunking and supervision features contemplated by the present invention by a detailed description of the operation of the system in establishing a connection.

Assume first that a subscriber at the manual substation 100 whose line terminates in the first exchange desires to converse with the subscriber at substation 300 whose line belongs to the second exchange. By removing his receiver from the hook, his line is associated in any well-known manner with a cord circuit 101 at an operator's position. The operator upon learning that connection is desired with a line belonging to a distant exchange, by means of her telephone set (not shown) then inserts the plug 102 of cord circuit 101 in the jack 103 of an outgoing trunk circuit 104, 105 leading to such exchange. Upon the insertion of the plug, a circuit is completed from ground, relay 106, sleeve of the plug and jack, relay 107, to battery. Relay 107 energizes and at its right-hand armature closes a circuit for displaying the supervisory lamp 108. At its left-hand armature, said relay also closes a circuit to place a guarding ground upon the selector multiple terminals 109 to hold the seized trunk busy in the event a subscriber at an automatic substation, such as substation 110, attempts to make a call to the second exchange over the trunk 104, 105. The following circuit is at the same time established to energize the stepping relay 111: battery, upper armature and back contact of relay 112, left-hand winding of low resistance relay 113, left-hand winding of relay 111, conductor 114, tip of the jack 103 and plug 102, upper right-hand wind-

ing of repeating coil 115, resistance 116, to ground. A parallel path from battery through relay 111 is also closed by the insertion of the plug 102 in jack 103. This circuit extends from battery, winding of supervisory relay 117, resistance 118, lower right-hand winding of repeating coil 115, ring of plug 102 and jack 103, winding of relay 119, left-hand winding of stepping relay 111, and to ground at the repeating coil 115 as above traced. The resistance of this path is so high, however, that sufficient current does not flow to energize relays 117 and 119. Consequently the supervisory lamp 120 remains extinguished and relay 119 at its armatures and contacts maintains the trunk 104, 105 telephonically disconnected from the operator's cord circuit 101 and the calling line.

By attracting its armature the stepping relay 111 at the calling exchange completes a circuit for the repeating relay 200 at the called exchange, Fig. 2, traceable from battery, left-hand winding of relay 200, contact 201 of relay 202, trunk conductor 105, polarized relay 121, right-hand winding of low resistance relay 113, front contact and armature of relay 111, trunk conductor 104, contact 203 of relay 202, right-hand winding of repeating relay 200, upper right-hand winding of repeating coil 204, to ground. The flow of current in this circuit is in such a direction as not to operate the polarized relay 121. Relay 200 energizes and closes a circuit for slow relay 205, which by attracting its left-hand armature prepares a circuit for the sending of impulses to the operating magnets of the first selector in the called exchange. At its right-hand armature, this slow relay 205 places a break point in the circuit of the release magnet 206, which circuit, as will hereinafter appear, is maintained open until the connection is taken down at the calling exchange. The operator having thus seized the trunk circuit 104, 105, now presses her calling key 122 and operates the impulse sending device 123 in accordance with the first digit of the called line. At each interruption by the sender 123 of the previously traced circuit for the stepping relay 111, said relay retracts its armature to open the bridge across the outgoing end of the trunk 104, 105, which in turn causes the repeating relay 200 to vibrate its armature correspondingly. At the first retraction of relay 200, the following circuit is closed for the first selector primary magnet 207, grounded armature and back contact of relay 200, left-hand armature and front contact of slow relay 205, left-hand armature and contact of relay 208, conductor 209, winding of slow relay 210, side-switch arm 225 (first position), winding of rotary stepping magnet 207, to grounded battery.

Magnet 207 energizes and advances shaft 211, carrying brushes 212, 213 and 214, one rotary step. The slow relay 210 also energizes and at its lower armature closes a circuit leading over the side-switch arm 215 to the escapement magnet 216. Said escapement magnet energizes preparatory to releasing the side switch to its second position. For each succeeding impulse transmitted over the trunk 104, 105 and repeated by the relay 200, the primary magnet 207 rotates shaft 211 to finally bring the brushes 212, 213 and 214 into operative relation to the group of trunk terminals containing the terminals 217, 218 and 219 of a trunk leading to a final selector switch. At the end of this series of impulses relay 200 remains energized and after a brief interval the slow relay 210 releases its armatures to open the circuit of escapement magnet 216. Magnet 216 thereupon deenergizes and passes the side switch into position 2.

When the side switch arrives in its second position, a new circuit is completed for escapement magnet 216, traceable from free pole of battery, winding of such magnet, contact and left-hand armature of release magnet 206, side-switch arm 215 (second position), conductor 220, contact 232, to ground at the side-switch arm 221. The escapement magnet energizes and closes a circuit including side-switch arm 222 (second position) for the secondary stepping magnet 223. This magnet upon energizing operates to step the positioned set of brushes 212, 213 and 214 onto the first set of terminals of the chosen trunk group, and at the same time severs its own circuit. At the end of this first step contact 232 is opened to thereby open the above traced circuit for the escapement magnet 216. If, however, the first trunk of the group is busy, there will be a ground present on test terminal 219 thereof, and the escapement magnet is held energized. The secondary magnet thereupon proceeds to advance brushes 212, 213 and 214 successively over the group until an idle trunk is found, at which time the escapement magnet deenergizes and passes the side switch to position 3.

The interexchange trunk 104, 105 has now been extended by means of a first selector at the second exchange, Fig. 2, to an idle trunk, such as trunk 301, 302, 303, leading to a final selector switch, Fig. 3, of a group of selectors having access to the called line.

The side switch of the first selector being in its third position, a circuit is completed as follows: ground, side-switch arm 224 (third position), brush 214, terminal 219, conductor 303, right-hand armature and back contact of the final selector release magnet 304, side-switch arm 305 (first position), winding of relay 306, to battery. Re-

lay 306 energizes and at its outer right-hand armature prepares a stepping circuit for the final selector operating magnets. At its left-hand armature said relay places a break point in the circuit of release magnet 304 to prevent a premature release of the switch. A ground is also applied from side-switch arm 224, the multiples 219 at other selectors, to prevent seizure of this trunk during the engaged period. The operator again manipulates her calling device 123 to send out the tens series of impulses, which impulses operate as before to vibrate the armature of repeating relay 200. At the first retraction of such relay, the following circuit is closed for the final selector primary stepping magnet 307; ground, armature and back contact of relay 200, left-hand armature and contact of slow relay 205, left-hand armature and contact of relay 208, conductor 209, winding of slow relay 210, side-switch arm 225 (third position), conductor 226, brush 212, terminal 217, conductors 301 and 308, outer armature and contact of relay 306, side-switch arm 309 (first position), winding of magnet 307, to battery. Magnet 307 energizes and advances the final selector brushes 310, 311 and 312 through one rotative step. At the same time the slow relay 210 attracts its armatures to complete a circuit for the escapement magnet 313. This circuit leads from ground, upper armature and front contact of magnet 210, side-switch arm 227 (third position), brush 213, terminal 218, conductor 302, side-switch arm 314 (first position), armature and contact of relay 315, winding of magnet 313, to battery. Magnet 313 energizes preparatory to advancing the side switch into its second position. For each succeeding impulse of the tens series the primary magnet 307 is operated to rotate the brushes 310, 311 and 312 into operative relation to the group of terminals containing those of the called line.

At the termination of this series, relay 200 holds its armature attracted and after an interval the slow relay 210 deenergizes to open the circuit of escapement magnet 313, which on retracting allows the side switch to go into second position. The relay 306 still remains energized over a circuit including its inner right-hand armature and the second position contact of side-switch arm 305, said arm 305 being designed to engage its second contact before breaking connection with the first contact.

The switch is now in condition to receive the final series of impulses, which are sent out as above described by the operator's calling device 123. In response to the first impulse of such series, and when the repeating relay 200 retracts its armature, a circuit is established for the secondary magnet 316 from the grounded armature of re-

lay 200, over the path previously traced to the side-switch arm 309, and thence to the magnet 316 and battery. The slow relay 210 again energizes and closes a circuit for escapement magnet 313, which leads from ground, the upper armature of relay 210, over the previously traced path of side-switch arm 314, now in position 2, to magnet 313 and battery. The magnet 313 energizes preparatory to releasing the side switch to position 3. At the same time a circuit is established for a slow relay 317, from battery, winding of such relay, side-switch arm 318 (second position), and thence to ground at the upper armature of slow relay 210. For each impulse of the final series the magnet 316 advances the brushes 310, 311 and 312 one step over the group and finally brings them to rest on the terminals 319, 320 and 321 of the called subscriber's line. Magnet 313 deenergizes as before, and steps the side switch into third position.

Assume first that, when the brushes 310, 311 and 312 arrive on the terminals of the called line, such line is already engaged. In this case, a non-selectable potential will be found on the test terminal 321, full potential having been removed or reduced in any well-known way in the event the line is busy as a calling line, or having been reduced by a circuit leading to ground at the left-hand armature and contact of a test relay 322 with side-switch arm 323 in third position, or to ground through the right-hand low resistance winding of relay 322 with side-switch arm 323 in position 4 at some other final selector if the line is busy as a called line. In either case, the test relay 322 of the switch shown does not receive sufficient current through its high resistance winding to energize. With the side-switch now standing in position 3, the energizing circuits of relays 306 and 317 are opened. As soon thereafter as relay 317 releases its right-hand armature the relay 306 becomes inert, thereby closing a circuit from battery, winding of release magnet 304, left-hand armature and contact of relay 306, primary off-normal contact 324 to ground. Release magnet 304 attracts its armatures and releases the brushes 310, 311, 312 and the side switch to normal position. As the switch reaches its normal position primary off-normal contact 324 is opened, which, however, does not occur until slightly after the closure of the normal contact 325. Hence the magnet 304 remains energized over the following circuit: battery, winding of magnet 304, left-hand armature of relay 306, normal contact 325, resistance 326, front contact and right-hand armature of magnet 304, to the grounded third wire 303. When the final selector side switch reaches its first position, a path is closed from the

secondary winding of busy tone transformer 327, contact and left-hand armature of magnet 304, side-switch arm 328 (first position), condenser 329, side-switch arm 330 (first position), to the trunk conductor 302 leading back to the first selector. In any well-known manner this busy tone is inductively transmitted back to the operator's telephone set. Being thus informed of the busy condition of the called line, the operator notifies the calling subscriber of such fact and removes the plug 102 from jack 108. The relay 111 thereupon deenergizes and opens the bridge across trunk conductors 104, 105, causing the repeating relay 200 to become inert. The slow relay 205 now deenergizes and closes the following circuit for the first selector release magnet 206: battery, winding of magnet 206, conductor 228, back contact and right-hand armature of relay 205, conductor 229, inner left-hand armature and back contact of relay 230, primary off-normal contact 231 to ground. Magnet 206 thereupon operates to restore the selector and its associated side switch to normal. When brush 214 moves off the terminal 219, ground is removed from wire 303 and the release magnet 304 retracts its armatures. At the calling exchange the removal of plug 102 also severed the circuit of relay 107, which retracted its armatures to efface the lamp 108, and to remove the busy condition from terminal 109. All apparatus is now in its normal restored position.

If, however, the called line 300 is idle at the time connection is extended thereto, full potential is present upon the test terminal 321. When the final selector side switch passes to third position the test relay 322 is therefore energized over a circuit including its high resistance winding. Relay 322 at its right-hand armature closes a circuit as follows: battery, winding of escapement magnet 313, contact and armature of relay 315, side-switch arms 314 and 318 (third position), right-hand armature and low resistance winding of relay 322 to ground. Relay 322 at its left-hand armature shunts out the high resistance winding, thus reducing the potential of test multiples 321 to make the called line non-selectable to other switches. A parallel circuit to the one just traced for magnet 313 is also completed for the slow relay 317 as side-switch arm 318 goes to third position. Relay 306 at this time remains energized to hold the release circuit open over a circuit from battery, winding of such relay 306, its inner right-hand armature and contact, contact and right-hand armature of the slow relay 317, to the grounded third conductor 303. The escapement magnet 313 energizing in the above traced circuit applies ringing current to the called line as follows: ringing source 130

331, relay 315, inner armature and contact of magnet 313, side-switch arm 332, brush 311, terminal 320, over the loop of substation 300, terminal 319, brush 310, side-switch 5 arm 333, to ground at the outer armature of magnet 313. When the called party responds the relay 315, being marginal, operates and opens the circuit of magnet 313, which deenergizes and passes the side switch 10 into position 4. In this position the relay 306 is maintained energized by a circuit leading over arm 305 to the grounded conductor 303. As side-switch arm 318 leaves position 3, the circuit for relay 317 is broken, 15 but being slow to release said relay holds its armatures for an interval subsequent to the arrival of arm 330 in position 4. This causes an impulse to be reverted to the first selector over the following circuit: grounded left- 20 hand armature and contact of relay 317, side-switch arm 330 (fourth position), conductor 302, terminal 218, brush 213, side-switch arm 227 (third position), upper armature and back contact of relay 210, 25 lower right-hand winding of repeating coil 204, relay 233, to battery. Relay 233 closes the following circuit for the first selector escapement magnet 216: grounded armature and contact of relay 233, conductor 234, side- 30 switch arm 215 (third position), left-hand armature and contact of magnet 206, magnet 216, to battery. The escapement magnet energizes, and as soon thereafter as the slow relay 317 retracts its armatures to open the 35 momentarily closed circuit of relay 233, said escapement magnet again deenergizes to escape the side switch to position 4. Upon the side-switch arms 227 and 235 reaching position 4, a circuit is closed for relay 233, 40 traceable from battery, winding of said relay, lower right-hand winding of repeating coil 204, upper armature and back contact of relay 210, side-switch arm 227 (fourth position), brush 213, terminal 218, conductor 45 302, side-switch arm 332 (fourth position), brush 311, terminal 320, over the loop of station 300, terminal 319, brush 310, side-switch-arm 333 (fourth position), conductor 301, terminal 217, brush 212, side-switch arm 50 235 (fourth position), upper right-hand winding of coil 204, to ground.

55 The relay 233 thus energizes in series with the called line, and operates to close a circuit for the trunk connecting relay 202 at the incoming end of the inter-office trunk circuit 104, 105. Such circuit leads from grounded armature and contact of relay 233, conductor 234, left-hand winding of relay 208, winding of relay 202, to battery. Relay 202 by attracting its armatures serves to remove the connection of trunk conductors 104, 105 with the windings of repeating relay 200 and to connect said conductors directly to the left-hand portion of repeating coil 204. The source of current fed to con-

ductors 104, 105 from the repeating coil 204 now flows in the proper direction for energizing polarized relay 121. Relay 121 accordingly attracts its armature and closes a circuit from battery, armature and front contact of relay 121, winding of relay 112, to ground at the right-hand armature of relay 107. Relay 112 energizes and locks up over a circuit extending from battery, upper armature and front contact of relay 112, winding of relay 112 to ground as before. By the attraction of both the armature of relay 121 and the upper armature of relay 112, the previously traced low resistance path from battery through the left-hand windings of relays 113 and 111 to ground at the upper right-hand winding of repeating coil 115 is now opened. This causes an increased flow of current through the supervisory relay 117 and trunk connecting relay 119 in the circuit hereinbefore described. Relay 117 energizes and closes a circuit for the called supervisory lamp 120, which is displayed to inform the operator that the called party has responded. Relay 119 by attracting its armatures electrically connects the trunk 104, 105 to the operator's cord circuit. When relay 200 was disconnected from conductors 104 and 105 by the relay 202 the circuit for relay 205 was at the same time opened. This relay being slow, however, does not deenergize until relay 236 has time to operate to close a holding circuit therefor. Premature release of the switches is thus prevented. The connection is now complete for conversation.

After conversation is finished the called subscriber by replacing his receiver opens the above traced circuit for relay 233. This relay in turn causes the deenergization of 105 trunk connecting relay 202, which disconnects the trunk 104, 105 from repeating coil 204, and again connects said trunk in series with the repeating relay 200. This results in a reversal of battery current 110 through polarized relay 121. Consequently relay 121 becomes inert and closes at its armature and back contact, a low resistance path from battery to ground as above traced in parallel with the circuit over which called 115 supervisory relay 117 is at this time being energized. This short circuit around relay 119 and 117 causes a sufficient reduction in current to permit their deenergization, the former relay opening the outgoing end of 120 the trunk 104, 105, and the latter relay serving to extinguish the lamp 120. The operator, thus being informed that conversation is finished, removes her plug 102 from the trunk jack 103. Restoration of the switching mechanism thereupon takes place as already described. 125

It will now be assumed that a subscriber at an automatic substation, as substation 110, belonging to the first exchange desires 130

to converse with the subscriber at substation 300. Upon the removal of the receiver at substation 110, the calling line is connected in a well-known manner, as by means of a line switch 127, 134 to a trunk leading to an idle selector switch whose brushes are shown at 128, 129 and 130. The subscriber now operates his dial 131 to position the selector brushes 128, 129, 130 in operative relation 5 to the terminals of trunks, such as terminals 132, 133 and 109 of trunk 104, 105, leading to the distant exchange to which the called line belongs. The selector then proceeds to automatically test the terminals 109 and in 10 the well-known manner brings its brushes 128, 129, 130 to rest in connection with the first idle trunk found. The following circuit is now closed for stepping relay 111: battery, upper armature and back contact of 15 relay 112, left-hand windings of relays 113 and 111, contact 135, terminal 132, brush 128, brush 127, over the loop of substation 110, brushes 134 and 129, terminal 133, relay 136, contact 137, right-hand winding of 20 relay 111, to ground. Relay 136 closes an energizing circuit for the supervisory relay 107, which completes a circuit for lamp 108. The operator is thereby informed that the trunk 104, 105 is engaged and will not at- 25 tempt to make connections with the same by means of her cord circuits. The stepping relay 111 attracts its armature and closes a bridge, including polarized relay 121, across the trunk conductors 104 and 105 to energize 30 the repeating relay 200 at the called exchange. This circuit is precisely the same as that traced in connection with an operator's call, the direction of current flow being such as not to affect the polarized relay 121.

40 By manipulating his dial 131 the subscriber at substation 110 causes the stepping relay 111 to vibrate its armature in a manner similar to that already described in connection with the operation of the operator's calling device 123. At each such interruption of the calling line, the relay 136 retracts, but relay 107 being slow to release does not have time to deenergize to efface lamp 108. From this point on, the operation 45 of stepping relay 111 under the control of the calling subscriber serves to bring about the operation of the first and final selectors at the called exchange, Figs. 2 and 3, as has already been explained. When the called 50 party responds and the trunk connecting relay 202 is operated to telephonically connect the incoming end of trunk 104, 105 to the called line, a current reversal results as before, and polarized relay 121 now becomes 55 energized. Relay 121 completes the circuit from its armature, through winding of the trunk connecting relay 112, to ground at relay 107. Relay 112, on acting, locks up over its own armature and connects the outgoing 60 end of the trunk circuit 104, 105 to the call- 65

ing line. A complete through telephonic connection is now established from the calling line in the first exchange to the called line in the second exchange and conversation may take place.

70 Since the system disclosed, illustrating the features of this invention, comprises one in which private branch exchanges are equipped with inter-exchange trunking facilities it is desirable that certain provisions be made to insure a high grade of transmission for this class of work. To such an end, means about to be briefly described are provided whereby an operator or a dial station subscriber of one exchange is 75 not able to seize a trunk leading to a second exchange for the purpose of calling the operator thereat, or for calling the central office. Considering this feature more specifically, it is to be noted that the selector 80 switches at each exchange, such as the switch shown in Fig. 2, which are used only in extending calls incoming from a distant exchange, are mounted on the multiple frame with the regular selectors which serve local 85 subscribers' lines. Therefore there appears in the multiples of the incoming switches shown in Fig. 2, trunks leading to both the exchange and central office operators. On calls made by subscribers, individual to the 90 exchange, the selectors therein provided to handle the local calls may be operated to extend such a calling line either to the local operator or to central office over a direct trunk thereto by sending the proper number of impulses to the switches. However, if an attempt is made by a calling line in a distant 95 exchange to make connection with the operator in a second exchange or to central office over a trunk outgoing from the second 100 exchange by dialing this predetermined number of impulses, the selector, such as that shown in Fig. 2, at the second exchange automatically restores to normal, refusing 105 to extend such a connection. This is accomplished by means of a wiper 237 carried on shaft 211, and arranged to wipe over the group contacts during the primary movement of the switch. Consequently if it is attempted to set the brushes 212, 213 and 110 214 in operative relation to trunks which lead either to the operator or to central office, the wiper 237 will, at the end of the primary movement of the switch, be resting on one of the contacts 238. As the side switch goes 115 to second position the following circuit is closed for the release magnet 206, and the switch returns to normal: battery, winding of magnet 206, conductor 239, one of the contacts 238, wiper 211, to ground at side-switch 120 224 (second position).

125 While the novel features of the present invention are set forth and described in connection with a trunking system for private branch exchanges, it is to be understood that 130

the said invention in its broader aspects is not to be limited to this particular class of work.

What is claimed is:

5. 1. In a telephone exchange system, subscribers' telephone lines, a trunk circuit, a connecting circuit associated with said trunk circuit, selective switches arranged to extend said connecting circuit to a called line, switching means for associating a calling line with said trunk circuit, means associated with a calling line for producing current impulses, said trunk circuit being arranged to transmit said impulses over its 10 70
- 15 two conductors in series, means responsive to such impulses for operating said selective switches, said trunk circuit being electrically disconnected from the calling line and said connecting circuit during the transmission of impulses, connecting means operated upon the response of the called subscriber for connecting said trunk to said connecting circuit, and a second connecting means responsive to the operation of said 20 75
- 25 first connecting means for connecting said calling line to the trunk circuit. 80
2. In a telephone exchange system, subscribers' lines, a trunk circuit, a connecting circuit associated with said trunk circuit, selective switches arranged to extend said connecting circuit to a called line, switching means for associating a calling line with said trunk circuit, means associated with the calling line for producing current 30 85
- 35 impulses, said trunk circuit being arranged to transmit said impulses over its two conductors in series, means responsive to such impulses for operating said selective switches, said trunk circuit being electrically disconnected 90
- 40 from the calling line and said connecting circuit during the transmission of impulses, a trunk connecting relay operated upon the response of the called subscriber for connecting the trunk to said connecting circuit, means operated by said relay for reversing the current in the trunk circuit, a polarized 95
- 45 relay responsive to such reversal of current, and a second trunk connecting relay responsive to the operation of said polarized relay for connecting said trunk circuit to the calling line for conversation. 100 105
5. In a telephone system, telephone exchanges, subscribers' lines terminating in each of said exchanges, a trunk circuit leading from one exchange to another, means for associating a calling line in the first of 110
- 55 said exchanges with said trunk circuit, selective switches at the other exchange for extending said trunk circuit to a called line therein, means for transmitting impulses over the two conductors of said trunk in 115
- 60 series, means responsive to such impulses for operating said selective switches, said trunk being in a non-talking condition during the transmission of impulses, means operated upon the response of the called subscriber 120
- 65 for electrically connecting said trunk to the called line, means operated by said connecting means for reversing the current in said trunk circuit, and means responsive to such reversal of current for electrically connecting said trunk circuit to the calling line for conversation. 125
6. In a telephone system, a first exchange, a second exchange, subscribers' lines terminating in said exchanges, a trunk circuit 130

outgoing from said first exchange and incoming to said second exchange, a connecting circuit at the second exchange, selective switches thereat for extending said connecting circuit to a called line, switching means at the first exchange for associating a calling line therein with said trunk circuit, means for sending impulses from the first to the second exchange over the two conductors of said trunk in series, means responsive to such impulses for operating said selective switches, said trunk circuit being electrically disconnected from said connecting circuit at its incoming end and from 10 said calling line at its outgoing end during the transmission of impulses, a relay operated upon the response of the called subscriber for connecting the incoming end of the trunk to said connecting circuit, means 15 operated by said relay for reversing the current in said trunk circuit, and a relay at the first exchange responsive to such reversal of current for connecting said trunk to the calling line.

25 7. In a telephone system, a first exchange, subscribers' lines terminating in said exchange, a second exchange, a trunk circuit leading from one exchange to the other, an operator's position in the first exchange, a 30 supervisory signal at said position, switching means at said position for associating a calling line with the trunk circuit, a connecting circuit at the second exchange, selective switches therein for extending such 35 circuit to a called line, means for sending impulses from the first to the second exchange over the two conductors of said trunk circuit in series, means in the second exchange responsive thereto for operating said 40 selective switches, said trunk being electrically disconnected from said connecting circuit and the calling line during the transmission of impulses, means operated upon the response of the called subscriber for 45 connecting the trunk circuit at its incoming end to said connecting circuit, means operated thereupon for reversing the current in said trunk, means operated in response to such current reversal for connecting the outgoing 50 end of said trunk to the calling line, and means also responsive to said current reversal for operating said supervisory signal.

8. In a telephone system, a first exchange, an operator's cord circuit therein, a calling line terminating in said cord circuit, a second exchange, a called line terminating therein, a one-way two conductor trunk outgoing from the first exchange and incoming to the second exchange, means for associating the operator's cord circuit with said trunk, a supervisory signal at the operator's position, selective switches at the second exchange for extending the incoming end of said trunk to the called line, means for sending 60 impulses from the first to the second 65 exchange from said first exchange and incoming to said second exchange, a connecting circuit at the second exchange, selective switches thereat for extending said connecting circuit to a called line, switching means at the first exchange for associating a calling line therein with said trunk circuit, means for sending impulses from the first to the second exchange over the two conductors of said trunk in series, means responsive to such impulses for operating said selective switches, said trunk circuit being electrically disconnected from said connecting circuit at its incoming end and from 10 said calling line at its outgoing end during the transmission of impulses, a relay operated upon the response of the called subscriber for connecting the incoming end of the trunk to said connecting circuit, means 15 operated by said relay for reversing the current in said trunk circuit, and a relay at the first exchange responsive to such reversal of current for connecting said trunk to the calling line.

exchange over the two conductors of said trunk, means responsive to such impulses for operating said selective switches, said trunk being disconnected from the cord circuit during the transmission of impulses, 70 means operated upon the response of the called subscriber for reversing the current in said trunk, a polarized relay operated by such current reversal, means responsive to the operation of said relay for connecting 75 said trunk to the operator's cord circuit for conversation, and means also responsive to said relay for operating said supervisory signal.

9. In a telephone system, two exchanges, 80 a two-conductor trunk outgoing from one exchange and incoming to the other, means for sending impulses over the two conductors of said trunk from one exchange to the other, means at the incoming end of said 85 trunk responsive to such impulses for extending the same to a called line, said trunk being open at its outgoing and incoming ends during the transmission of impulses, means operated upon the response of the 90 called subscriber for closing said trunk at its incoming end and for simultaneously reversing the current therein, and means operated in response to such current reversal for closing the outgoing end of said trunk 95 for conversation.

10. In a telephone system, subscribers' lines, an operator's position, a supervisory signal thereat, a trunk circuit terminating at one end before said operator's position, 100 a selective switch at the other end of said trunk, means at the operator's position for associating a calling line with said trunk, means for sending impulses over said trunk, means responsive thereto for operating said 105 switch to extend said trunk to a called line, said trunk being open at both ends during the transmission of impulses, means operated by the response of the called subscriber for closing both ends of said trunk for conversation and for reversing the current therein, and means operated in response to such current reversal for displaying said signal.

11. In a telephone system, a manual subscriber's line, an automatic subscriber's line, an outgoing trunk line, an operator's position, means at said position for connecting the manual subscriber's line to the outgoing end of said trunk, an automatic switch for 115 connecting the automatic subscriber's line to the outgoing end of said trunk, two signals at the operator's position, a relay, means for operating said relay when either of said subscribers' lines is connected to said trunk, 120 means controlled by said relay for operating one of said signals and for rendering the trunk busy at said automatic switch, a called line, means for extending said trunk to the called line, and means operated by the re- 125 130

sponse to the called subscribers for rendering effective the other of said signals.

12. In a telephone system, a manual subscriber's line, an automatic subscriber's line, 5 an outgoing trunk line, an operator's position, means at said position for connecting the manual subscriber's line to the outgoing end of said trunk, an automatic switch for connecting the automatic subscriber's line to 10 the outgoing end of said trunk, a signal at the operator's position, a relay, means for operating said relay when either of said subscribers' lines is connected to said trunk, and means controlled by said relay for operating said signal and 15 for rendering the trunk busy at said automatic switch.

13. In a telephone system, a manual subscriber's line, an automatic subscriber's line, an outgoing trunk line, an operator's position, means at said position for connecting 20

the manual subscriber's line to the outgoing end of said trunk, an automatic switch for connecting the automatic subscriber's line to the outgoing end of said trunk, a signal at the operator's position individual to said trunk, a relay, means for operating said relay when either of said subscribers' lines is connected to said trunk, means controlled by said relay for operating said signal and for rendering the trunk busy at said automatic switch, means for sending impulses over said trunk when either of said lines is connected thereto, and switching means at the other end of said trunk responsive to 25 said impulses.

In witness whereof, I hereunto subscribe my name this 19th day of March, A. D. 1918.

ALBEN E. LUNDELL.
